HANDLE

Isaac S. Keeler, Grand Rapids, Mich., assignor to
Keeler Brass Company, Grand Rapids, Mich.

Application March 23, 1934, Serial No. 717,003

5 Claims. (Cl. 292—347)

The main object of this invention is to provide a handle for door latches and the like, which is attractive in appearance and at the same time is strong and durable and economical to produce.

A further object is to provide a structure in which the handle bar is conformed to constitute a back plate and a support for the outer casing member.

10 Objects relating to details and economies of my invention will appear from the description to follow. The invention is defined and pointed out in the claims.

15 A structure which is a preferred embodiment of my invention is illustrated in the accompanying drawing, in which:

Fig. 1 is a view in front elevation of a handle embodying the features of my invention.

20 Fig. 2 is a side elevation, a portion of the spindle being broken away.

Fig. 3 is a longitudinal section on line 3—3 of Fig. 1.

Fig. 4 is a transverse section on line 4—4 of Figs. 2 and 3.

25 Fig. 5 is a transverse section on line 5—5 of Figs. 1 and 3.

Fig. 6 is a perspective view of the spindle housing sleeve or ferrule.

In the illustrated embodiment of my invention, numeral 1 indicates the spindle of the latch and 2 an escutcheon or door plate for the spindle. I have not shown the door nor the latch proper as the relation of these parts to the spindle and escutcheon will be well understood by those skilled in the art.

30 At the outer end of the spindle, I fixedly secure the handle bar 3 which is generally of channel section and has outwardly facing transversely rounded channels 4, 4 along its side edges providing lateral flanges 5, 5. The web of the handle bar is suitably conformed to provide a rear step or socket 6 adjacent the end of the spindle 1. Over this handle bar, I arrange an outer casing member 7 having a longitudinally fluted web 8 35 engaging the edges of the lateral flanges 5, 5, the casing member having inturned flanges 9, 9 at its edges engaging the rounded channels 4, 4 as illustrated. The ends of the casing member are folded over the ends of the handle bar, the handle bar being tapered towards its rounded ends as shown.

40 The housing sleeve or ferrule 10 for the spindle 1 has a flared foot 11 terminating in a flange 12 conformed to the shape of and seated in the 45 socket or step 6 of the handle bar 3 for rotation

therewith. The ferrule is held in place by means of the compression spring 13 disposed in the escutcheon 2.

With the parts arranged in this manner, the handle bar not only constitutes a back plate for the assembly but also acts as a support for the outer casing member which is of relatively thin sheet metal such as stainless steel or brass. The rounded edges of the handle make it attractive in appearance and at the same time provide a 10 smooth "feel", especially at the back. The structure is economical to produce, light in weight, and strong and durable.

15 I have illustrated and described my improvements in an embodiment which I have found very practical. I have not attempted to illustrate or describe other embodiments or adaptations, as it is believed this disclosure will enable those skilled in the art to embody or adapt my improvements as may be desired.

20 Having thus described my invention, what I claim as new and desire to secure by Letters Patent is:

1. In a handle structure of the class described, the combination with a spindle, of a handle bar 25 fixedly secured to the outer end of said spindle and having outwardly facing transversely rounded channels along its side edges providing lateral flanges, the web of said handle bar being conformed to provide a rear socket adjacent said 30 spindle, an outer casing member embracing said handle bar and having a longitudinally fluted web engaging the edges of said lateral flanges, the casing member having inturned flanges at its edges engaging said rounded channels and the 35 ends of the handle bar, and a spring pressed spindle housing sleeve having a flared foot terminating in a flange conformed to the shape of and seated in said socket for rotation with the handle.

40 2. In a handle structure of the class described, the combination with a spindle, of a handle bar fixedly secured to the outer end of said spindle and having outwardly facing transversely rounded channels along its side edges providing lateral 45 flanges, and an outer casing member embracing said handle bar and having a longitudinally fluted web engaging the edges of said lateral flanges, the casing member having inturned flanges at its edges engaging said rounded channels and the 50 ends of the handle bar.

3. In a handle structure of the class described, the combination of a handle bar of channel section having outwardly facing transversely rounded channels along its side edges providing lateral 55

flanges, and an outer casing member of channel section embracing said handle bar and having a web engaging the edges of said lateral flanges, the casing member having inturned flanges at 5 its edges engaging said rounded channels and the ends of the handle bar.

4. In a handle structure of the class described, the combination with a spindle, of a handle bar secured to the outer end of said spindle and 10 having transversely rounded channels along its rear edges, and an outer casing member directly embracing said handle bar and having inturned rounded flanges at its rear edges engaging said

rounded channels, the handle bar constituting a back plate and a support for said casing member.

5. In a handle structure of the class described, the combination with a spindle, of a handle bar secured to the outer end of said spindle and having transversely rounded rear edges, and an outer casing member embracing said handle bar and having inturned rounded flanges at its rear edges engaging said rounded rear edges, the handle bar constituting a back plate and a support for 10 said casing member.

ISAAC S. KEELER.
